UNITED STATES PATENT OFFICE.

ARTHUR J. BRAUER, OF ST. LOUIS, MISSOURI.

TENNIS-RACKET CASE OR COVER.

1,091,280.

Specification of Letters Patent. Patented Mar. 24, 1914.

Application filed March 3, 1913. Serial No. 751,803.

To all whom it may concern:

Be it known that I, ARTHUR J. BRAUER, a citizen of the United States, and residing at St. Louis, in the State of Missouri, have invented certain new and useful Improvements in Tennis-Racket Cases or Covers, of which the following is a specification.

This invention relates to cases or covers for tennis rackets and the like.

10 A tennis racket cover is usually provided with a side opening closed by a flap, which flap is usually secured in closed position by a suitable fastener. In opening the flap to withdraw the racket, and in withdrawing the racket through the side opening, the fabric is liable to tear and the stitched seam is liable to rip at the ends of the opening and at the points where the ends of the flap are stitched or joined to the body of the 20 cover.

The objects of this invention therefore are to construct a tennis racket cover which is provided with end reinforcing means of simple construction so as to prevent tearing or ripping at the ends of the opening and the flap when the flap is opened or when the racket is withdrawn.

Further objects will appear from the detail description taken in connection with the 30 accompanying drawing in which:

Figure 1 is a front view of a tennis racket cover embodying this invention, Fig. 2 is an enlarged view of the upper end of the cover with the flap raised, Fig. 3 is an enlarged 35 detail view of the cover near one of the ends of the flap showing the reinforcing means, Fig. 4 is an inside perspective view of the cover showing the flap raised and showing the connection of the reinforcing means with 40 the body and binding of the cover, Fig. 5 is a detail perspective view showing the arrangement of the ends of the flap reinforcing binding with the edge binding of the cover, and Fig. 6 is a perspective view partly 45 in section showing the relative arrangement of the binding for the outside edge of the cover, the edge binding for the opening and the binding for the flap.

Referring to the accompanying drawing 50 10 designates a tennis racket cover the body of which is composed of layers of canvas or any other suitable fabric or material seamed together by a line of stitches 9. A binding 11 extends around the outside edge of the 55 cover body and is secured by a line of stitches 12 passing through the binding and through

the layers of material forming the body. A side opening 13 is formed in the cover and the lower edge of this opening is provided with an edge binding 14 secured by a line 60 of stitches 15, while the ends of this binding extend underneath the outside binding 11 and are secured by the lines of stitches 9 and 12.

The layer of material 16 forming one side 65 of the upper part of the cover extends over and below the opening 13 to form a flap 17. This flap is provided with an edge binding 18 secured by a line of stitches 19 and the ends 20 of this binding extend underneath 70 the outside binding 11. The ends 20 extend for short distances along the edge of the cover and are secured in position by means of the lines of stitches 9 and 12. The flap 17 is formed of a double thickness of material as shown in Fig. 3 and the upper edge 75 of the inside layer is provided with a binding 21 stitched thereto by a line of stitches 27, a line of stitches 28 also passing through the binding and through the outside layer 80 of the flap. The ends 22 of the binding 21 extend underneath the outside edge binding 11 and for short distances along the edge of the cover and these ends are secured by means of the lines of stitches 9 and 12. 85 The binding 21 extends in an arc along the lower face of the flap 17 as shown in Fig. 2. The body of the cover and the flap are provided with coöperating members 23 and 24 forming a snap fastener. A handle 25 90 is secured to the cover by means of rivets 26.

In the manufacture of the cover the bindings 14, 18 and 21 are sewed on the fabric before the two layers of material comprising the cover are sewed together. In sewing 95 the layers together the ends 20 and 22 are tucked between these layers and secured in position by the line of stitches 9. When the outside binding 11 is sewed on, the line of stitches 12 will also pass through the ends 100 20 and 22 and firmly secure these ends. The bindings 14, 18 and 21 provide means for reinforcing the cover at the ends of the opening. It will be noted that the ends 22 of the binding 21 on the inside face of the flap 105 extend therefrom at the ends of the side opening closed by the flap, underneath the outside edge binding, in a direction opposite to the direction which the flap is moved to open it, and therefore in a direction opposite 110 to the direction of pull on the flap. When the flap is opened the strain will not come

on the fabric or on the stitches in such a way as to rip the seams, but this strain will come on the binding 21 which is secured at its ends by comparatively long lines of stitches 5 to the body of the cover and to the outside binding 11. In view of the fact that the binding 21 extends completely across the flap in an arc the strain is uniformly distributed over the entire canvas cover body. 10 These bindings are made of leather or other suitable tough material which will not tear.

It is obvious that various changes may be made in the details of construction without departing from the spirit of this invention 15 and it is therefore to be understood that this invention is not to be limited to the specific construction shown and described.

Having thus described the invention what is claimed is:

- 20 1. A tennis racket cover having a side opening, a flap for said opening, and a binding running across and secured to the inside face of said flap and extending therefrom at the ends of said opening along the edges of the cover body in a direction opposite to the direction which the flap is moved to open it, and secured to the body along the edges thereof to form reinforcing means.
- 25 2. A tennis racket cover having an outside edge binding and a side opening, a flap for said opening, and a binding on said flap extending therefrom at the ends of said opening along the edges of the cover body and underneath said outside edge binding in a direction opposite to the direction which the flap is moved to open it, and secured underneath said outside edge binding to form reinforcing means.
- 30 3. A tennis racket cover having an outside

edge binding and a side opening, a flap for 40 said opening, and a binding on said flap running in an arc across and secured to the inside face of said flap and extending therefrom at the ends of said opening along the edges of the cover body and underneath 45 said outside edge binding in a direction opposite to the direction which the flap is moved to open it, and secured underneath said outside edge binding to form reinforcing means.

4. A tennis racket cover having a side opening, a flap for said opening, and bindings on said flap extending in opposite directions from the ends of said flap and along the edges of the body and stitched to the 55 body of the cover at the ends of said opening to form reinforcing means.

5. A tennis racket cover having an edge binding and a side opening, a flap for said opening, and bindings on said flap extending 60 in opposite directions from the ends of said flap and along the edges of said body and underneath said edge binding to form reinforcing means.

6. A tennis racket cover having an edge 65 binding and a side opening, a flap for said opening, bindings on said flap extending in opposite directions from the ends of said flap and along the edges of said body and underneath said edge binding, and a binding for 70 the edge of said opening extending underneath said edge binding.

In testimony whereof I affix my signature in the presence of these two witnesses.

ARTHUR J. BRAUER.
